UNITED STATES PATENT OFFICE.

H. WILLIAM ATWATER, OF BOSTON, MASSACHUSETTS.

WATER-CLOSET.

SPECIFICATION forming part of Letters Patent No. 251,813, dated January 3, 1882.

Application filed June 30, 1880. (No model.)

To all whom it may concern:

Be it known that I, H. WILLIAM ATWATER, of Boston, in the county of Suffolk and State of Massachusetts, have invented certain Improvements in Water-Closets, of which the following is a full, clear, concise, and exact description, reference being had to the accompanying drawings, in which—

Figure 1 is a vertical section of a water-closet embodying my invention. Fig. 2 is a side view, partly in section, on a small scale. Fig. 3 is a front elevation of the lower part of the closet. Fig. 4 is a section on line xx of Fig. 1.

In my Patent No. 214,984, dated May 6, 1879, I have described an attachment for use with ordinary water-closets, and that attachment forms a part of the improved water-closet shown in the drawings.

The main object of my present invention is to construct a water-closet which will not only operate properly, so far as concerns carrying off the excrement, but will also effectually prevent gases escaping houseward from the sewer or soil pipe; and my invention consists in the combination, in a water-closet, of a gate or valve to close the discharge-orifice of the bowl, this gate or valve being self-acting when its retaining-stop is withdrawn, and a second gate or valve to close the discharge-orifice of the overflow-pipe leading from the bowl, the first valve serving to hold the water in the bowl, and both valves opening toward the sewer and serving to prevent gas from passing houseward.

In the drawings, A is the bowl, well-known without description. It is supported in casing B, and casing B is connected with plate d, which forms a cover to casing d', and casing d' rests upon plate d², the two plates d d² being held together as shown, and the chamber thus formed contains the valve d³. The soil-pipe F is connected to plate d². The valve d³ closes the discharge-orifice a and holds the water in the bowl up to the level a' when the rod G is down, so that no gas can escape houseward through orifice a.

In closets of this class—that is, where the orifice a is closed by a valve held in place until the contents of the bowl are to be discharged—an overflow, a², is a necessity, and this overflow (see Fig. 2) I also close with a valve, a³, opening toward the sewer, so that the gases are ef-

fectually prevented from entering the bowl A. The details of construction of the valve a³ and its adjuncts are fully shown in my Patent No. 214,985, dated May 6, 1879.

After the closet has been used the valve d³ is opened wide, and at the same time the water-supply valve (not shown) is opened, the contents of the bowl A escaping through soil-pipe F, and fresh water flowing into the bowl in the usual way, so that when valve d³ and the water-supply valve are both closed a sufficient supply of fresh water will enter the bowl to bring the water-level up to the line a', the surplus, if any, escaping by the overflow a².

The main feature of my invention consists in the construction and mode of operation of the valve d³. In my closet valve d³ is balanced upon its lever d⁴, so that the pressure of the lever upon it is all exerted near its center, and the rod G serves only as a stop to lever d⁴, reinforcing the counter-weight d⁵, which counter-weight d⁵ is sufficient to close the valve d³, but not sufficient to hold it against the head of water in bowl A. These two features (the balancing of the valve upon its lever and the use of the rod G as a stop only) are important parts of my invention. The button d⁶ may be fast to valve d³ and connected to lever d⁴ by a pin which fits loosely in the hole through the rib of the button, but in practice I prefer to have the button d⁶ disconnected from the valve d³ and to form a neck, d⁷, upon one edge of the valve, this neck having an eye through which the pin d⁸, which forms the journal of lever d⁴, passes, the pin d⁸ fitting loosely in the eye of neck d⁷. A light leaf-spring, d⁹, upon the valve is useful, as it not only aids the counter-weight d⁵ to return valve d³ quickly to its seat, but also prevents the escape of water, &c., toward the pin d⁸. A rubber ring, d¹⁰, shaped as shown, forms the seat of valve d³.

The rod G has a foot, g, which acts as a stop to lever d⁴, and its weight g' aids the counter-weight d⁵ in holding valve d³ on its seat against the head of water in bowl A, the counter-weight d⁵ being only heavy enough to return valve d³ to its seat, but the weight g' being sufficiently heavy to hold it firmly to its seat against the head of water in bowl A. When the rod G is raised, after the closet has been used, the water, &c., in bowl A escapes all at

once, the valve d^3 opening freely, as it is held only by the counter-weight d^5 . This valve then closes (for the foot g is out of the way of the end of lever d^4) so far as the gradual flow of water 5 through the bowl A allows, and remains nearly closed all the time that the rod G is held up after the first sudden discharge of the contents of bowl A. As the chamber formed by $d d' d^2$ is full of sewer-gases the rod G should be properly packed where it passes through plate d . This is well effected by the rubber disks $g^2 g^3$, the upper one, g^2 , being compressed between collars g^4 and g^5 when the rod G is down, and the lower one, g^3 , between foot g and collar g^6 10 when rod G is lifted. Rod G is lifted by chain g^7 , which is attached to the handle by which the water-supply valve is actuated. It is obvious that other devices may be used for actuating rod G. In practice I have found that 15 shown to act well.

The casing d' is best made with an opening in front closed gas-tight by a plate, as shown in Fig. 3, which is a front elevation of the casing d' and its adjuncts, and in Fig. 4, which is 20 a section on line xx of Fig. 1. The chamber 25

d^{11} , projecting upward from plate d^2 , is also best made with the front portion, d^{12} , detachable, as shown in Figs. 1 and 4. When these parts are thus made the valve d^3 is readily got at in case of any obstruction.

30

What I claim as my invention is—

1. In a water-closet, an outlet-valve counterbalanced to close the outlet when the bowl is empty and to open it when the bowl is filled to a designated depth, in combination with a 35 weighted stop, g , which, when raised, leaves the outlet-valve free to act and when lowered prevents the outlet-valve from opening, substantially as described.

2. In a water-closet, the combination of a 40 bowl having an outlet-valve which is self-acting when its retaining-stop is withdrawn with an overflow-pipe and its outwardly-opening valve, substantially as and for the purposes set forth.

H. WILLIAM ATWATER.
